UNITED STATES PATENT OFFICE

139,151

DESIGN FOR A DRAWBAR FOR HARROWS

Bernard Landen, Ida Grove, Iowa

Application July 29, 1944, Serial No. 114,641

Term of patent 14 years

(Cl. D39—1)

To all whom it may concern:

Be it known that I, Bernard Landen, a citizen of the United States and a resident of Ida Grove, in the county of Ida and State of Iowa, have invented a new, original, and ornamental Design for a Drawbar for Harrows, of which the following is a specification, reference being had to the accompanying drawing, forming part thereof, in which:

Fig. 1 is a perspective view of a drawbar for harrows showing my new design;

Fig. 2 is a plan view of the same; and

Fig. 3 is a rear elevation of Fig. 2.

I claim:

The ornamental design for a drawbar for harrows, substantially as shown.

BERNARD LANDEN.
